UNITED STATES PATENT OFFICE.

MARY A. BENJAMIN, OF FREDONIA, NEW YORK, ADMINISTRATRIX OF
AUGUSTUS J. BENJAMIN, DECEASED.

LINOTYPE-MACHINE.

No. 820,546.

Specification of Letters Patent.

Patented May 15, 1906.

Application filed December 30, 1905. Serial No. 293,867.

To all whom it may concern:

Be it known that AUGUSTUS J. BENJAMIN, deceased, late a citizen of the United States, and a resident of Cassadaga, in the county of 5 Chautauqua and State of New York, did in his lifetime invent an Improvement in Linotype-Machines, of which the following is a specification.

This invention relates to linotype-machines, and has for its principal object to provide a machine in which an auxiliary set of matrices may be employed in connection with the ordinary keyboard, assembling-channels, and other portions of the machine, 15 so that the operator may be enabled to set up type of different character.

A further object of the invention is to provide the commercial Mergenthaler linotype-machine with an auxiliary reservoir carrying 20 an additional set of matrices and to provide means whereby the keyboard may be connected to the matrix-discharging devices of the ordinary magazine or the auxiliary magazine at the will of the operator.

A still further object of the invention is to provide a two-reservoir machine having escapements for controlling the discharge of the matrices with means for transmitting the operative movement of the reed or escapement-bars to either set of escapements, so that matrices from one or other of the magazines may be directed into the assembler, and, further, to provide for the ready adjustment of the connections, so that a portion of 35 the line may be set with matrices from one reservoir and the remaining portion with matrices from the other reservoir.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a sectional elevation of sufficient of a linotype-machine to illustrate the invention. Fig. 2 is a detail view of a portion of the same, showing the fulcrum-bar adjusted to a different position. Fig. 3 is a sectional plan view

of a portion of the device on the line 3 3 of Fig. 2. Fig. 4 is a detail perspective view of one of the angle-bars in which the ends of the cross-bars are supported. Fig. 5 is a detail perspective view of one of the cross-bars and 60 the lower end of the escapement-operating rods.

Similar characters of reference are employed to indicate corresponding parts throughout the several figures of the drawings.

In the drawings, A indicates the ordinary magazine of the commercial Mergenthaler linotype-machine, and B the escapement mechanism ordinarily employed for controlling the discharge of the matrices therefrom. This reservoir is of the type commonly employed and may contain matrices bearing one, two, or more letters, as desired. In addition to the reservoir A a second reservoir 10 70 is employed, and said reservoir is arranged to contain another set of matrices, preferably bearing type of a character different from those in the first reservoir. The auxiliary reservoir is provided with an escapement 75 mechanism 11 of the usual construction.

The keyboard mechanism C is of the well-known type and imparts motion through the medium of the usual rollers c, cams d, and arms e to escapement-bars or reeds 15, which in the present instance are much shorter than those usually employed and do not extend directly to the escapement devices which control the discharge of the matrices from the reservoir or reservoirs, as usual, provision 80 being made for transmitting the movement of the escapement-bars or reeds to one or other of the escapement mechanisms B 11 in accordance with the character of matrices to be directed to the assembler.

At a point above the escapement-bar-operating mechanism is a frame that is provided with a pair of cross-bars 17, forming supports for a pair of parallel angle-bars 18, said angle-bars having their horizontal webs directed 90 toward each other and secured in spaced relation to the bars 17. Each of the angle-bars is provided with a series of webs or flanges 19, which, in connection with the vertical and horizontal webs of the angle-bars, form pockets for the reception of cross-bars 20, said bars bridging the space between the two angle-bars and their opposite ends being received within said pockets. Pivots 100 connected to the central portion of each of the 105

bars 20 is one of the sets of escapement-bars or reeds 15, there being one set of escapement-bars or reeds for each key of the machine, and whenever one of the keys is depressed movement will be transmitted through one set of escapement-bars or reeds and cross-bar 20, connected thereto, will be correspondingly raised. One end of each bar 20 is pivotally connected to the lower end of a rod 22, the upper end of said rod being operatively connected with its respective escapement B. The opposite end of said bar is connected to a rod 23, and the upper end of said rod 23 is operatively connected with its respective escapement mechanism 11. The pivot-studs which connect the bar 20 to the rods 22 and 23 are also provided with small disks or rollers 24, that fit within the pockets of the angle-bars, and when in position of rest the rollers belonging to each bar will engage with both the horizontal and the vertical webs of said angle-bars, as shown in Fig. 1. In the opposite ends of the frame 16 are arranged guides for the reception of slide-bars 26, and said slide-bars form the support for a fulcrum-bar 27, which may be moved to the position shown in Fig. 1 or to the position shown in Fig. 2, in accordance with the escapement mechanism to be operated—that is to say, when adjusted to the position shown in Fig. 1 the escapement member 11 will be operated and when adjusted to the position shown in Fig. 2 the escapement member B will be operated.

35 The two slides 26 are connected by a cross-bar 30, from which extends a latch-bar 31, having a finger-piece 32 within convenient reach of the operator, and the latch-bar is provided with notches 33 and 34, either of which may 40 be engaged with a stud or rib 35, that is carried by a portion of the stationary frame 16, a spring 36 serving to hold the bar in either position to which it may be adjusted.

It will be noted that the fulcrum-bar 27 45 rests against the disks 24 and while confining the cross-bars 20 and the vertical rods in place will not interfere with the free swinging of the free ends of the bars 20 of the pivot-pins by which they are connected to the vertical bars.

50 The machine may be operated in the ordinary manner, and in order to change from one style of type to another—that is to say, to effect the discharge of matrices from either the magazine A or the magazine 10—it is merely necessary for the operator to adjust the latch-bar 31 in order to shift the fulcrum-bar 27, and in this manner a line may be assembled from one or other or partly from 55 both of the magazines.

Having thus described the invention of the said AUGUSTUS J. BENJAMIN, what is claimed is—

1. In a machine of the class described, a

plurality of magazines, independent escapement mechanisms for controlling the discharge of matrices from said magazines, a keyboard-controlled actuating mechanism having a permanent connection with said escapement mechanisms, and an adjustable means for rendering one of the connections idle, and permitting the transmission of operative movement to the other mechanism.

2. In mechanism of the class described, a plurality of reservoirs, escapement mechanisms for controlling the discharge of matrices from the reservoirs, escapement-rods, a cross-bar forming a linked connection between the lower portions of said escapement-rods, a keyboard-controlled escapement-actuating mechanism connected to said cross-bar, and an adjustable means for holding one or other end of the bar and permitting movement of the opposite end thereof to operate one or other of the escapement-rods.

3. In mechanism of the class described, the combination with a plurality of reservoirs, of independent escapements for controlling the discharge of matrices therefrom, independent escapement-rods for transmitting movement to said escapements, a cross-bar forming a linked connection between the lower portions of said rods, an adjustable means for holding one or other end of the cross-bar stationary and forming a fulcrum for movement of the other end of the bar, and a keyboard-controlled actuated mechanism connected to said cross-bar.

4. In mechanism of the class described, the combination with a plurality of reservoirs, of independent escapements for controlling the discharge of matrices from said reservoirs, a frame, a pair of opposed angle-bars supported thereby and provided with ribs or partitions dividing the angle-bars into pockets, cross-bars having their opposite ends arranged in the pockets, escapement-actuating bars pivotally connected to the opposite ends of the cross-bars, disks carried by the pivots and resting against the walls of the angle-bars, a keyboard-controlled actuating mechanism connected to the central portions of said cross-bars, a pair of spaced slides, a fulcrum-bar carried thereby and extending above the cross-bars, and a latch-lever for moving the slides and fulcrum-bar to adjust the latter into engagement with one or other set of disks.

In testimony whereof I have hereunto set my hand, this 12th day of December, 1905, in the presence of two subscribing witnesses.

MARY A. BENJAMIN,
Administratrix of the estate of Augustus J. Benjamin, deceased.
